UNITED STATES PATENT OFFICE.

HIRAM W. RANSOM, OF CINCINNATI, OHIO, ASSIGNOR OF ONE-HALF TO
THE EMERSON & FISHER COMPANY, OF SAME PLACE.

RACK FOR WHEELS.

SPECIFICATION forming part of Letters Patent No. 293,783, dated February 19, 1884.

Application filed December 17, 1883. (No model.)

To all whom it may concern:

Be it known that I, HIRAM W. RANSOM, of the city of Cincinnati, in the county of Hamilton and State of Ohio, have invented certain new and useful Improvements in Racks for Wheels, of which the following is a specification.

My invention has for its object the provision of means for the storing of vehicle-wheels in an orderly and compact manner, and also for enabling wheels, after being painted and while the fresh paint thereon is drying, to be turned, so that the paint or varnish will be kept evenly distributed upon the surface of the wheel.

The several features of my invention and the several advantages arising from their use, either conjointly or otherwise, will be apparent from the following description:

20 In the accompanying drawings, Figure 1 represents a side elevation of one end of a single rack illustrating my invention. Fig. 2 represents a front elevation of a rack, and showing one kind and arrangement of slots for the reception of the wheels. Fig. 3 represents a front elevation of a rack, and showing the preferred form and arrangement of slots. Fig. 4, Sheet 2, is a side elevation of a quadruple rack. Fig. 5 is front elevation of the 30 rack shown in Fig. 4. Fig. 6 is a top view of the upper racks shown in Fig. 4, when the upper rails of said racks have been removed. Fig. 7 is an enlarged side elevation of a preferred form of piece for forming the slots upon the rack-rail when the slots are as shown in Fig. 3. Fig. 8 represents in end elevation the preferred mode of supporting a quadruple rack, the figure being on a much smaller scale than other figures representing said rack.

40 In order to fully illustrate my invention, I will first describe my single rack, and afterward specify a desirable mode, also of my invention, of combining together two or more racks made according to my invention.

45 In Fig. 1 is shown a single rack. A A indicate the lower rack-rails, suitably supported, and B the upper rack-rail, likewise suitably supported. Both the lower rails, A A, and upper rail, B, are rigidly secured in position.

On the upper part of the lower rack-rails are 50 projections *a*, and on the lower part of the upper rail are the projections *b*. Between the projections *a* are the openings or slots *a'*, and between the projections *b* are the openings or slots *b'*. The slots *a'* may be cut in rails A, in 55 which event the projections *a* will be in one piece with the rail; or the projections may consist of a separate piece or pieces of material and be suitably connected to the rails A. In like manner the projections *b'* may be in one 60 piece with the rail B, or consist of separate piece or pieces suitably connected to the last-named rail. The rails A and B run substantially parallel to one another. The upper rail, B, is not only located in a higher horizontal plane than rails A, but is also, when viewed at end, preferably located in a vertical plane to one side of the vertical center plane or point between the lower rails, A, and is sufficiently far to one side of said center to 70 allow the center of gravity of the wheel, when placed in the rack, to fall between the rail B and rails A.

When it is not necessary to place the wheels to be racked very close together, the bottoms 75 of the slots *a'* may be on the same level, and be so far apart that the distance between the adjacent wheels placed in adjacent slots in the rack will be equal to or greater than the sum of the lengths of those portions of the hubs of 80 said wheels which are on the adjacent sides of the said wheels, as shown in Fig. 2. In such a case the slots *b'* are preferably the same distance apart as are the slots *a'*, and are preferably in the same vertical transverse plane. 85

The wheel to be racked is placed in a slot, *a'*, of lower rails, A, and in that slot *b'* of upper rail, B, which is in the same vertical plane as said last-named slot *a'*. The weight of the wheel will now retain it safely in position in 90 the rack. When the slots are thus far apart, the hubs of adjacent wheels will not in any way interfere. Ordinarily, however, it becomes desirable to place the wheels close together in the rack, and to accomplish this, and yet prevent the hubs of adjacent wheels from interfering, I have invented the following mode of racking them: In the lower rails, A,

I make the bottoms of the slots a' to be at different distances above the rail. Thus I make, preferably, every other slot, which I will denominate $a'm$, so that its bottom shall be a given distance above the rail A , and I make the bottom of the slot which I will denominate $a'n$, and which comes to a slot, $a'm$, lower down than the bottom of the slot $a'm$. In like manner on rack-rail B the bottoms of the slots which I will denominate $b'n$, and which are in the vertical plane with the slots $a'm$ of the front lower rack-rail, are higher up—*i. e.*, farther away from the axial center of the rack—than the bottoms of the slots $b'm$, which are in the same vertical plane with the slots $a'n$ of the front lower rack-rail. The slots $a'm$ and $a'n$ may be placed much closer together than when the bottoms of the slots are all on the same level, as shown in Fig. 3, and the slots $b'm$ and $b'n$ of upper rail, B, may be closer together than when the bottoms of the slots are as shown in said Fig. 3. A slot $a'm$ in the front lower rack-rail, and a slot $b'n$ in the upper rack-rail and a slot $a'n$ in the rear lower rack-rail are in the same transverse vertical plane. Also, slot $a'n$ in the front lower rack-rail and slot $b'm$ in the upper rack-rail and slot $a'm$ in the lower rear rack-rail are in the same vertical plane. When a wheel, which I will name R, is placed in slot $a'm$ in the forward lower rack and in $b'n$ of the upper rack and in slot $a'n$ of the rear lower rack, (see Fig. 6, left-hand rack,) the front part of its periphery will set high, and the rear portion of the wheel will set low, and as an entirety the wheel will set low and backward. A wheel, which I will denominate S, set in the adjacent slot $a'n$ of the lower front rack-rail and slot $b'm$ of the upper rack-rail and in slot $a'm$ of the rear lower rack-rail will set low in front and high behind, and as an entirety will set high and forward. For this reason that portion of the hub (wheel R) which is on the left hand of the wheel in Fig. 3 will be behind and below that portion of the hub of the wheel S which is on the right hand of the wheel in said Fig. 3. This arrangement of the wheels and hubs is also shown in Fig. 1. The adjacent end of the hub of wheel R will then be so near to the spokes of wheel S and the adjacent end of the hub of wheel S will then be so near to the spokes of wheel R that if the wheels R and S stood on a level floor and the wheel S were moved forward, its hub would overlap and strike the hub of wheel R.

Placed in the racks having slots $a'm$ and $a'n$, $b'm$, and $b'n$, the hubs of adjacent wheels cannot collide, but will "dodge" each other, and the wheels can nevertheless be placed so closely together in the rack that the distance between their felloes shall not exceed four inches. By the use of such a rack I am enabled to save about three-quarters of the space and room necessarily heretofore employed in storing wheels. Another advantage resulting from

the employment of racks such as hereinbefore described consists in enabling the newly-painted wheels to be thoroughly dried in a handsome and workmanlike manner. For instance, after a wheel has been painted or varnished, it is placed in the rack. Here it is held upright, and its coat of paint or varnish well protected from being injured; but as the paint or varnish is drying and runs down toward the bottom of the wheel, the latter can be readily and quickly revolved a third or half turn by applying the hand to the face or periphery of the wheel at the point T and pushing upward. For the better enabling the pressure of the hand to effectuate such partial rotation of the wheel, the upper rack-rail, B, should be placed in about the position shown in Figs. 1 and 4. Then, as the fore part of the wheel is lifted upward, the wheel will easily revolve without especial friction against the bottom of the slot of the upper rack. For the purpose of still further economizing room, I have devised a novel mode of combining a number of these racks. For example, I place two racks, one above the other, A A being the lower rack-rails of the lower rack, and B the upper rack-rail of this lower rack, and A' A' being the lower rack-rails of the upper rack, and B' the upper rack-rail of this upper rack. The racks may have projections forming slots $a'b'$, or one rack may have slots $a'b'$ and the other have slots, as $a'm a'n b'm b'n$. Preferably, however, both the racks have the slots $a'm a'n b'm b'n$, as heretofore shown in Fig. 2. The rack-rails are suitably supported. In the upper rack I preferably place hind wheels, and in the lower rack the front wheels of vehicles, (the latter being of less diameter and extending less far out from the rack into the room,) for the reason that space in the neighborhood of the floor is usually of more value than the space higher above the floor. Two of such pairs of racks as have been just described may be compactly united, being placed back to back, as shown in Fig. 4, A' A' being the lower rack-rails of the additional lower rack, and B' the upper rack-rail of the same, A' A' being the lower rack-rails of the additional upper rack, and B' the upper rack-rail of the same. The rails A' A' and A' A' are preferably respectively provided with slots $a'm a'n$, and the rails B' and B' with slots $b'm b'n$, in the manner heretofore mentioned.

For still further economizing space, I place the slots in rack-rails A A and B in relation to the slots in rack-rails A' A' and B' so that the planes of the slots in rails A A and B will pass between the planes of the slots in rails A' A' and B', and I likewise preferably locate the slots in the rack-rails A' A' and B' in such relation to the slots in the rack-rails A' A' and B' that the planes of the slots of the rails A' A' and B' will pass between the slots of rails A' A' and B'. Thus the rear portion of the wheels of one lower rack can be passed between the rear portion of the wheels of the

adjacent lower rack. In like manner the rear portion of the wheels of one upper rack can pass between the rear portion of the wheels of the other upper rack; and for the purpose of causing the wheels of one rack to thus pass between the wheels of another rack, I bring the rails A A nearer to rails A' A', rail B nearer to rail B', rails A² A² nearer to rails A³ A³, and rails B² and B³ nearer together. Thus these four racks occupy much less space than double the space that either one lower and one upper rack would occupy. By such an arrangement of racks I am enabled to save at least seven-eighths of the room heretofore necessarily occupied in storing a given bulk of wheels. I am also enabled to save much time in reaching and taking out such wheel or wheels as are desired. I am also enabled to provide a means for securely and safely keeping the wheels on store, and a novel, convenient, and valuable means and mode for enabling the paint or varnish, after being applied to wheels, to be properly dried.

Any suitable mode of supporting the rails 25 of the rack is to be employed. A desirable mode of supporting the quadruple rack is as follows: The rack-rails A A A' A' are secured to the floor. At each end is a central upright, D, preferably secured to the floor. Each 30 upright D carries a cross-piece, E, and to the latter are secured the rack-rails B B' and rails A² A² A³ A³. Higher up, each upright D carries a second cross-piece, F, to which are attached the rails B² B³. Braces G G, running from 35 the upright upward to the ends of cross-piece E, to stiffen and aid in supporting the latter, may be employed. (See Fig. 8.)

A preferred mode of forming the slots a' m 40 n or b' m b' n is by forming pieces K, in the center of which is the slot a' m or b' m, as the case may be, according as the pieces are intended for a lower or an upper rack-rail. The pieces K are then secured by suitable means, preferably by nails, to the rack of which they 45 are to form a part. These pieces K are so fastened to the rack as to leave an opening or slot between their adjacent ends suitable for the insertion of the felly of the wheel. This last-named opening will form the slot a' n or b' 50 n, heretofore mentioned. The sides of each slot, whatever the distance its bottom may be from the rail, is preferably tapered, enlarging from the bottom toward its mouth. Thus no part of the wheel except the tire will come in 55 contact with any portion of the rack.

The rear lower rack-rail may be omitted when the slots or grooves in the forward lower rail and upper rail are sufficiently deep and long; but such a construction is not as desirable as the one having all three rails. Of course, the two lower racks can be employed without the two upper racks, and vice versa.

Any suitable form of projection a or b may be employed. For example, round pins may 60 be employed.

While the various features of my invention

are preferably employed together, one or more of them may be employed without the remainder, and when desired one or more of said features may, so far as applicable, be employed 70 in connection with racks other than those herein specifically described.

What I claim as new, and desire to secure by Letters Patent, is—

1. In a rack for wheels, the combination of 75 the two lower rack-rails and the upper rack-rail, each provided with transverse slots, substantially as and for the purposes specified.

2. The combination of the two lower rack-rails and the upper rack-rail, each provided 80 with transverse slots, the upper rack-rail being located behind the vertical central plane between the lower rails, substantially as and for the purposes specified.

3. The combination of the lower rack-rails 85 and upper rack-rail provided with slots whose bottoms are alternately nearer to and farther from the axial center of the particular rack to which said slots belong, substantially as and for the purposes specified.

4. The combination of the lower rack-rails provided with slots a' m a' n, and upper rack-rail provided with slots b' m b' n, the slots a' m of the forward lower rail and the slots b' n in the upper rail and a' n in the lower rear rail 90 being in the same transverse plane, and the slots a' n of the forward lower rail and the slots b' m of the upper rail and a' m of the rear lower rail being in the same transverse plane, substantially as and for the purposes specified. 95

5. The combination of a lower rail, A, and an upper rearwardly-placed rail, B, provided with transverse slots, substantially as and for the purposes specified.

6. Two contiguous racks having lower rails 100 and upper rails provided with slots, the bottoms of the slots on rack-rail alternating in height, substantially as set forth, and the planes of the slots of one rack passing between the planes of the slots on the other rack, substantially as and for the purposes specified. 105

7. The combination of two contiguous racks, the rails being provided with transverse slots, the planes of the slots in one rack passing between the planes of the slots in the other rack, substantially as and for the purposes specified. 115

8. The combination of the four racks having the rails A A A' A' B B' A² A² A³ A³ B² B³, provided with transverse slots, substantially as described, and uprights D and cross-pieces E 120 F, substantially as and for the purposes specified.

9. The combination of the four racks two above and two below, placed back to back, and the rails thereof being provided with transverse slots, the upper racks being adapted to receive hind wheels, and the lower racks to receive front wheels, substantially as and for the purposes specified.

10. The combination of an upper and lower 130 rack having rails provided with transverse slots, the upper rack being adapted to receive

hind wheels, and the lower rack to receive front wheels, substantially as and for the purposes specified.

11. In a rack, the combination of the separate blocks K, having slots $a' m$ or $b' m$, and the rack-rail, the ends of the adjacent blocks forming the slots $a' n$ or $b' n$, substantially as and for the purposes specified.

12. In a rack, the rails A A and B, provided with transverse slots having inclined sides, to substantially as and for the purposes specified.

HIRAM W. RANSOM.
